CHRISTIAN F. DILG, OF NEW YORK, N. Y., ASSIGNOR TO CHARLES H. J. DILG.

BALL-BEARING.

1,117,808.

Specification of Letters Patent.

Patented Nov. 17, 1914.

Continuation of application Serial No. 655,652, filed October 18, 1897. This application filed April 6, 1910.
Serial No. 553,897.

To all whom it may concern:

Be it known that I, CHRISTIAN F. DILG, a citizen of the United States of America, and a resident of New York, in the county 5 and State of New York, have invented a certain new and useful Ball-Bearing, of which the following is a specification, the same being a continuation of my application Serial No. 655,652, filed October 18, 10 1897.

My invention relates to ball holding devices, and particularly to that class of ball bearings wherein a holder is used, having a series of ball bearing points to retain the 15 balls, the latter projecting beyond the device, in the inner and outer, and in the upper directions with respect thereto, and it has for its object the provision of an organization of the class described, simple in construction, inexpensive to manufacture, and which operates in a smooth, easy and noiseless manner in practical use.

To attain the desired end, this, my invention, consists in the construction, arrangement and operation of the parts herein set forth.

In the drawings which accompany and form a part of this specification, Figure 1 represents a plan view of a ball holder embodying my invention; Figs. 2 and 6 are plan views of two ball holding devices constructed according to my invention, Figs. 3, 4, 5 and 7 are views in detail of some modified forms of ball holding devices embodying my invention, Fig. 8 is a longitudinal section of a portion of a hub with one of my ball retaining devices; and Figs. 9 and 10 are respectively views of blanks of which the retaining devices shown in Figs. 2 and 40 6 are made.

Like letters of reference indicate like parts in all the views.

I have found it desirable to devise a ball bearing of simple construction, and one that 45 will be reliable and efficient, as well as noiseless, in practical use, in which the balls are held in their normal positions by means of a retaining device, and I have, therefore, constructed according to my invention, an 50 organization of the kind set forth, embodying the preferred construction of parts and their mutual relationship, combination, arrangement and organization in a composite body or structure, as hereinafter described.

55 Referring particularly to the drawings. A

denotes my ball holding device located in the chamber formed by the inner flanges of the hub A², and the cones of the axle A²², of the present embodiment, and comprising ordinarily a practically horizontal ring having a series of inner and outer bearing points or detents, to retain the balls B.

In Figs. 2 and 5 I have illustrated modified forms of my invention. In the embodiment illustrated in these figures the edges of the walls of the recesses A⁴ formed between the upper portions A¹² of the ring, are preferably parallel with each other, and the same extend upward above the center line of the balls B; the side walls a² of the same, 60 these intermediate portions in this instance extending radially or transversely of the ring, in connection with the bottom portion of said ring, constituting the recesses A⁴; which walls a² are preferably inclined to 65 toward the balls in order that the upper portions of each recess will be somewhat smaller than the lower part thereof. My bearing points or detents consist, in this instance, of one or more vertical prongs, as a³ 70 in Fig. 3, located in the inner and outer portions of the recess A⁴, or lateral prongs, as a⁴ in Fig. 4, located along the inner and outer edges of the side inclined portions of 75 my ring A. If preferred, however, the parts 80 of my ring, forming the lower portions of said recesses, may be of circular form, as A²⁰, shown in Fig. 5, or they may be rectangular, as A³⁰, Figs. 6 and 7, constituting the recesses A⁴, and to the upper portions, 85 as A³¹, of my ring, as in Figs. 6 and 7, may be secured, as by pins a¹³, supplementary plates A¹³, provided with projecting retaining portions or points a⁵, formed by the 90 same being laterally recessed or concaved, 95 the said top portions being wider at their outer edge than at the inner edge thereof.

It will be apparent from a consideration of the several forms of my invention illustrated and described that it comprises a 100 ring-shaped device having a base portion that serves as a support upon which rests the series of balls, that from this base portion of the retainer there are bent up a series of members designated a² in the drawings, and termed herein "side walls," as they serve to separate from each other the recesses in which are confined the individual balls, though these members may also with 105 propriety be termed standards or flaps, and 110

such terms are thus sometimes employed herein, and that the upper ends of these side walls (otherwise termed standards or flaps) are bent over and form a series of 5 tapering top portions, designated A^{12} in Figs. 2, 3, 4 and 5 of the drawings, and A^{31} in Figs. 6 and 7 thereof, are arranged substantially parallel with the base portions of the retainer and in angular relation to the 10 side walls (otherwise termed standards or flaps) that rise therefrom, so that they extend outward from the side walls more or less over the recesses for the balls, the latter being retained in the holder when it is 15 moved from the ball race or bearing.

The side walls α^2 (otherwise termed standards or flaps) that rise from the base may be perpendicular thereto, as indicated in Fig. 7 or inclined thereto, as represented in Figs. 20 3, 4 and 5 while the top retainers carried by the said side walls may be integral therewith, as indicated in Figs. 4, 5, 6 and 7, or 25 of a compound two-part nature, including plates secured to the top portions as indicated in Figs. 6 and 7. Further, the edges of the top retainers that bound the recesses in which are situated the balls, may be 30 straight and substantially parallel with each other, as indicated in Fig. 4, or they may be of a substantially concave contour, as indicated in Fig. 6, this latter construction for some purposes being the one which I prefer. In both constructions, indicated respectively in Figs. 2 and 6, the top retainers extend 35 outwardly, that is, they are radially disposed (each considered as a whole)—extending from a position substantially over the inner edge of the ring to a position substantially over the outer edge thereof, and 40 they are each laterally enlarged, that is, each portion or extension is larger or wider at its outer portion than at its inner portion. This construction results in the production of a top retaining member for the balls having 45 sharp corners or pointed ends. When these top retainers are constructed as indicated in Fig. 6, that is, with the edges that bound the ball recesses made concave, the pointed edges thereof are emphasized, as indicated 50 at α^5 in Fig. 3. The advantages incident to this latter construction arise from the fact that by concaving the opposite edges of the top retaining extensions the balls are allowed to project upward, that is, away 55 from the base support, and out of their recesses, to a greater extent than where the opposite edges are straight, as indicated in Fig. 2. When the holder is formed as indicated in Figs. 8 and 9, the parts of 60 the top retainers designated A^{31} , extend outward from the side walls (otherwise termed standards or flaps), as clearly indicated in Fig. 7, so as to lie over and retain the balls.

65 It is manifest that various omissions of

some particulars could be made without materially affecting the essential features of my invention, or the operation of the remaining parts, and I do not therefore, wish to be limited to the specific structural details of the organization set forth herein. Obviously, the elements of the structure described may be located at an angle to the plane in which they are shown. I, accordingly, use the words "horizontal," "vertical," and the like, in a relative sense.

In operation, the balls B, are placed in the recesses between each pair of inner and outer bearing points or projections, and top bearing points, so that they project beyond the same in the inner and outer and in the upper directions. The balls are thus securely held in place, and by means of the construction shown, are allowed to move quite a long distance radially, and they are thus enabled to adjust themselves, in case of any wearing of the bearing taking place, the side bearing points, as stated, preventing the balls from rolling out of their sockets, in either a vertical, radial or lateral direction, which balls may be readily snapped in and out of the retainer, at will.

Obviously, my ball retaining device may be advantageously employed in many kinds of bearings or sockets, and I do not therefore wish to limit myself to the use of my device in connection with ball bearings of the kind shown alone.

As it is evident that many changes in the construction and relative arrangement of parts might be resorted to without departing from the spirit and scope of my invention, I would have it understood that I do not restrict myself to the particular construction and arrangement of parts shown and described, but that such changes and equivalents may be substituted therefor, and that

What I claim as my invention, is:

1. An annular ball-holding device comprising supporting means for balls, intermediate portions projecting upwardly from the said supporting means in approximately radial directions, and top retainers joining the intermediate portions and overhanging the supporting means and projecting somewhat over a part of the surfaces of the balls.

2. An annular ball-holding device comprising a base constructed and arranged to support the balls, top portions extending substantially parallel to the base, intermediate portions joining the base and top portions, and top retainers comprising a series of supplementary plates, one plate attached to each top portion, the plates being arranged to extend partially over the curved surfaces of the balls.

3. A ball-retaining device for ball bearings consisting of a ring comprising a se-

ries of upwardly extending parts, and also a series of practically horizontally-positioned parts superimposed over the ring, the said practically horizontal parts being wider at their outer edge than at the inner edge thereof.

4. A ball-retaining device for ball bearings consisting of a ring comprising a series of upwardly extending parts, and also a series of practically horizontally-positioned parts superimposed over the ring, the said practically horizontal parts being wider at their outer edge than at the inner edge thereof, and having the side edges of the same concaved.

5. A ball-retaining device for ball bearings consisting of a ring comprising a series of upwardly extending parts, and also a series of practically horizontally-positioned parts superimposed over the ring, the said practically horizontal parts being wider at their outer edge than at the inner edge thereof, and having at the outer and inner edges of the same points projecting into the ball holding recesses.

6. A ball-retaining device for ball bear-

ings consisting of a ring comprising a series of upwardly extending parts, and also a series of practically horizontally-positioned parts superimposed over the ring, the said practically horizontal parts being wider at their outer edge than at the inner edge thereof, and having the side edges of the same concaved, and having at the outer and inner edges of the same points projecting into the ball holding recesses.

7. A ball-retaining device for ball bearings consisting of a ring comprising a series of upwardly extending parts, and also a series of practically horizontally-positioned parts superimposed over the ring, the said practically horizontal parts having the side edges of the same concaved.

In testimony of the foregoing specification, I do hereby sign the same in the city of New York, county and State of New York, this second day of March, 1910.

CHRISTIAN F. DILG.
